UNITED STATES PATENT OFFICE.

MORRIS F. BELL, OF FULTON, MISSOURI.

DESIGN FOR BOXES.

Specification forming part of Design No. **8,886**, dated January 4, 1876; application filed December 11, 1875.
[Term of Patent 3½ years.]

To all whom it may concern:

Be it known that I, MORRIS FRED. BELL, of Fulton, in the county of Callaway, in the State of Missouri, have invented a Design for Boxes, of which the following is a specification:

The nature of my design is fully represented in the accompanying photographic illustration, to which reference is made.

A is the body of the box, which is of a shape suited to the articles for which it is intended—viz., the accouterments and regalia of Knights Templar, Knights of Pythias, I. O. O. F. Encampment, &c. The door is placed at the bottom, and to the side opposite the door is affixed an ornamental handle, a. The sides of the box are octagonal in shape, the upper and lower corners being of unequal length, and the

panels B are ornamented with a design representing a combination of a cross, a wreath, and a lyre, and the letters "P. C." or some other emblematic design and letters may be substituted for this. An ornamental brass hand, b, surrounds the box on both edges, as shown.

What I claim as my invention is—

The design for an ornamental box, herein shown, having octagonal sides A, ornamented with a cross, a wreath, and a lyre, in combination with emblematic letters or figures, substantially as herein shown and specified.

MORRIS FRED. BELL.
